EXERCISING MACHINE

Paul K. Cowgill, Escondido, Calif.

Application March 15, 1954, Serial No. 29,506

Term of patent 7 years

(Cl. D34—5)

Fig. 2

Fig. 1

Fig. 3

To all whom it may concern:

Be it known that I, Paul K. Cowgill, a citizen of the United States, residing at Escondido, in the county of San Diego and State of California, have invented a new, original, and ornamental Design for an Exercising Machine, of which the following is a specification, reference being had to the accompanying drawing, forming a part thereof, and wherein:

Figure 1 is a perspective view of an exercising machine showing my new design;

Figure 2 is a top plan view thereof; and

Figure 3 is an end elevational view of my new design taken from the right hand end of Figure 1.

I claim:

The ornamental design for an exercising machine, as shown.
